DOUBLE DISK GATE VALVE

Edmund H. Lunken, Hartsdale, N. Y., assignor to
The Lunkenheimer Company, Cincinnati, Ohio,
a corporation of Ohio

Application April 3, 1936, Serial No. 72,502

2 Claims. (Cl. 251—63)

This invention relates to an improvement in valves and particularly to double disk gate valves.

It is an object of this invention to provide means for easy attachment and detachment of the valve disks of a double disk gate valve to and from the valve stem.

It is a further object of this invention to provide such means of attachment of the valve disks to the stem wherein upon removal of the valve stem from the valve casing, the valve disks will remain attached together and to the valve stem in such a manner as to be easily detached from one another and from the valve stem without the use of special or unusual tools.

It is a further object of this invention to provide such means, wherein the attachment of the valve disks to one another and to the valve stem is accomplished by the use of a single cotter or pin.

It is a further object of this invention to provide such means of connecting the valve disks together as will permit of limited universal movement of the valve disks with respect to one another in order to secure close fit, during operation, between the valve disks and their respective seats in the valve casing.

It is a further object of this invention to provide cooperating guide means for the purpose of preventing misalignment or binding of the valve disks in their travel from the closed position, wherein they are in close abutment with the valve seats, to the open position in which they are partially or wholly withdrawn from such contact, and vice versa.

In the drawing:

Figure 1 is a side elevational view, partly in section, of a valve having my invention applied thereto, with the valve disks in seated position;

Figure 2 is a view similar to Figure 1, but showing the valve disks in a position removed from the valve seats, the upper part of the valve having been broken away;

Figure 3 is a sectional view of the valve in the position shown in Figure 2, taken on the line 3—3 of Figure 2;

Figure 4 is an elevational view of one of the valve disks shown in Figures 1 and 2, as seen from the inner side thereof; and

Figure 5 is a similar view of the other valve disk, as seen from the inner side thereof.

Referring to the drawing in detail, the valve casing 1 is equipped with threaded pipe connections 2 and 3, which are adapted to receive screw threaded portions on pipes attached to the valve

casing 1. Adjacent the threaded portion 2 is a chamber 4, while a like chamber 5 is disposed adjacent the threaded portion 3. An aperture 6 leads from the chamber 4 through the inclined web 7 into a central chamber 8 of the valve casing which is adapted to receive the valve disks. A flat annular valve seat 9 is disposed at an inclination to the vertical on the inner face of the inclined web 7. An aperture 10 leads from the chamber 5 through the web 11 into the central chamber 8. The web 11, like the web 9, is inclined with respect to the vertical but in a reverse direction. The web 11 has a seat 12 disposed thereon. The valve casing 1 has an upwardly extending portion which terminates in a threaded portion 14, which is adapted to threadedly receive the valve bonnet 15.

The valve bonnet 15, at the end adjacent the threaded portion 14 of the valve casing 1, has an interiorly threaded portion 16. At the top portion of the valve bonnet 15 is formed a packing space 17, which is adapted to receive packing 18 therein. A cap member 20 is threaded on the exteriorly threaded portion 19 of the stem casting and is adapted to engage a packing gland member 21 in order to draw it downwardly against the packing 18 in the packing space 17 for a purpose which will hereinafter appear.

Disposed axially within the valve bonnet 15 is a valve stem 22 which has a threaded portion 23 at the lower end thereof, which threaded portion is adapted to cooperate with the interiorly threaded portion 16 of the valve bonnet 15. The portion of the stem 22 above the threaded portion 23 thereof is cylindrical, save at its extreme top end, where it terminates in a square portion 24 and screw portion 25. The square portion 24 is adapted to receive thereover a complementary portion in the hand wheel 26, and these complementary portions are secured together by means of the nut 27 which is screw threaded on the screw portion 25 of the stem 22. Rotation of the hand wheel 26, due to the engagement of the threaded portion 23 of the stem with the threaded portion 16 of the stem guide will cause axial movement of the stem 22 in the valve bonnet 15. At the lower end of the stem 22 is a head portion 29, which is separated by a reduced portion 28 from the lower end of the threaded portion 23 of the valve stem.

A pair of valve disks 30 and 31 is secured together for limited universal movement in a manner which will be hereinafter described, and they are adapted to be reciprocated vertically in the central chamber 8 of the valve casing 1 by en-

agement of the head portion 29 of the valve stem 22 with semi-annular socket 32 in the valve disk 30 and semi-annular socket 33 in valve disk 31. The valve disks 30 and 31 are generally similar and the semi-annular sockets 32 and 33 are identical and identically disposed with respect to the valve disks. The outer faces of the disks are inclined in substantially the same manner and at substantially the same angle from the vertical, 10 as are the valve seats 9 and 12 respectively. The valve disk 30 is designated the female disk and has, centrally arranged in its inner face, a substantially hemispherical recess 34. At each side of the recess 34 is a lug 35 which extends axially 15 with respect to the recess 34 at each side thereof. Extending horizontally through the lugs 35 and radially with respect to the disk 30 is a pair of cotter or pin receiving bores or holes 36. Extending outwardly from opposite sides of the disk 30 20 is a flange 37, each of which is adapted to loosely engage a groove 58 vertically disposed in opposite sides of the valve casing 1 to guide the disk 30 in its vertical movement therein. Extending through the inner faces of the flanges 37 in the 25 same direction as the holes 36 in lugs 35 are depressions 38 which are of greater diameter than the holes 36. The disk 31 is designated the male disk and has a centrally arranged substantially hemi-spherical boss 44 which is adapted to engage the recess 34 in the female disk 30. A hole or bore 46 extends axially through the boss 44 and is adapted to be aligned with the holes 36 in the respective lugs 35 on the female disk 30. Enlarged countersinks or depressions 45 are disposed 30 at each side of the boss 44 and extend in the same direction as the hole 46 in the boss 44.

Flanges 47 similar to flanges 37 of disk 30 and similarly disposed have depressions 48 on the inner face thereof, which are of cylindrical or 40 elongated contour and coaxial with the hole 46 in the boss 44. A stop lug 39 is disposed on the inner face of the lug 30 opposite the semi-annular socket 32 and is adapted to engage a stop lug 49 on the disk 31 to limit inward movement of the 45 lower surfaces thereof and prevent head 29 from accidental displacement from the sockets 32 and 33.

In assembling the valve disks and stem, the disks are placed together with the respective semi-annular sockets 32 and 33 embracing the head portion 29 of the stem 22, the boss 44 of the male disk 31 being disposed in the recess 34 of the female disk 30. The hole 46 in the boss 44 is aligned with the holes 36 in the lugs 35 on the 50 disk 30 and a cotter pin 50 is inserted therethrough, entrance of the cotter to the holes 36 and 46 being provided for by the recesses 38 and 48 in the respective valve disks. The respective flanges 37 and 47 have their outer faces adapted 55 to slidably engage the guide grooves 58 in the casing 1. Axial movement of the valve stem 22 will cause reciprocation of the connected valve disks 30 and 31 in the guide grooves 58 in the valve casing 1. The connection of the valve disks 60 30 and 31 to one another and to the valve stem 22 and the engagement of the flanges 37 and 47 of the respective plates in the guide grooves 58 is sufficiently loose to permit of a desired amount 65 of universal movement of the valve disks 30 and 31 with respect to one another. This movement is, of course, limited by the stop lugs 39 and 49 on the respective disks. The attachment, by means of the cotter 50, prevents accidental detachment of the disks 30 and 31 from the stem 70 22 because, before the head portion 29 of the stem

22 is released from the sockets 32 and 33, the cotter 50 must first be removed from its connecting relation. This removal of the cotter 50 is preferably accomplished by manipulation of the hand wheel 26, screwing the stem 22 upwardly a sufficient distance to remove the respective valve disks 30 and 31 from their seats. When this has been accomplished, the valve bonnet 15 may be unscrewed from the threaded portion 14 of the valve casing 1. The valve bonnet, valve stem and attached valve disks 30 and 31 may be bodily removed upwardly from the valve casing 1. After this removal has been accomplished, the cotter may be removed by the use of a cotter pulling tool or may be driven out, by means of a punch, from its position in the holes 35 and 36, and the disks 30 and 31 may then be removed from the stem 22 for the purpose of re-facing or replacing these members. It is to be particularly noted that, by my invention, the stem 22 may be removed 20 from the valve casing 1 without accidental detachment therefrom of the valve disks 30 and 31.

It is to be understood that the cotter which is shown to be of the split or expanding type may be of any desired type of pintle member and that, when use is made of such a cotter as has been illustrated, the expansion thereof may be so slight as to permit of its removal without the use of tools, while at the same time the cotter is prevented from axial displacement by the engagement of the 30 respective flanges 37 and 47 with the grooves 58 in the valve casing 1.

Furthermore, when an expanding type of cotter, as shown, is used it will provide a slight desirable amount of resiliency in the connection between the valve disks which will prevent the occurrence of "hammer" upon operation of the valve. It is, of course, to be understood that, when such cotters are used, the resiliency thereof will prevent axial displacement of the pin relative to the holes 36 and 46 in the respective disks. In using cotters of simple cylindrical type, such pins are preferably of a length more nearly equal to the distance between the grooves 58 of the valve casing and the heads thereof are preferably provided with surfaces which will slide with little friction in the grooves 58.

It is to be understood that the above description and illustration in the drawings is merely illustrative and in no wise limiting, and that I desire to comprehend within my invention such modifications as come within the scope of the claims and the invention.

Having thus fully described my invention, what I claim as new and desire to secure by Letters Patent is:

1. In a valve having seats adapted to be engaged by a pair of relatively movable valve disks connected to an axially movable valve stem having a head thereon; means for connecting said disks to said stem comprising a pair of sockets in said disks adapted to rotatably receive the head of said stem, and means of connection between said disks comprising complementary apertured projecting parts on each of said disks and a removable pin extending through said apertures said disks having thereon cooperating stop projections on the opposite side of said pin from said sockets whereby to limit relative motion about said removable pin to retain the head of said stem in said sockets until said removable pin is removed.

2. In a valve having a casing with opposed seats adapted to be engaged by the outer faces of a pair of valve disks having oppositely disposed guide flanges adapted to engage guide grooves in

opposite sides of said casing and to be moved in said guides by an axially movable stem having a head thereon; means for connecting said disks together, for limited relative movement, and to 5 said stem comprising an arcuate recess in the inner face of one disk, a pair of lugs at opposite sides of said recess having holes therethrough disposed transversely of the stem, an arcuate boss

in the other disk having a hole therethrough, a semi-annular socket in each disk, said sockets being complementary and being adapted to rotatably receive the head of said stem, and a pin extending through the holes in said boss and said lugs and being retained from displacement therefrom by the walls of said casing. 5
